UNITED STATES PATENT OFFICE.

SIDNEY HERBERT DONALDSON, OF HAMPSTEAD, ENGLAND.

TYPE-WRITING MACHINE.

No. 844,264.

Specification of Letters Patent.

Patented Feb. 12, 1907.

Application filed December 16, 1905. Serial No. 292,032.

To all whom it may concern:

Be it known that I, SIDNEY HERBERT DONALDSON, a subject of the King of England, residing at 6 Boundary Road, Hampstead, in the county of London, England, have invented certain new and useful Improvements in Type-Writing Machines; and I do hereby declare the following to be a full, clear, and exact description of the invention, such as will enable others skilled in the art to which it appertains to make and use the same.

This invention relates to a method of obtaining marginal adjustments on type-writing machines, and refers particularly to the class of indicators in which the rotation of the platen-roller is arrested after a given number of revolutions, partial or complete, in order to regulate the vertical height or position upon the paper of the first, last, or any other line of type-writing.

The usual form of my invention consists of a box or case of metal or other suitable material, attached by means of a clip, clamp, screw, or the like to the frame of the paper-carriage and may be adapted to most standard makes of type-writers. The case contains gearing which is actuated by a gear-wheel fixed frictionally or otherwise upon the shaft of the platen-roller. The box or case is, by preference, of a semicircular form at the upper portion, and consists of metal plates joined together by a band or rim of metal. A spindle passes through the center of both side plates and has a fixed pointer upon the front end and a milled head or knob at the back end. On the inside of the box or case is fixed a gear-wheel, so placed in the case as to engage, while the spindle is in its normal position, with a pinion, which forms part of a train of a diminishing gear, which, as before mentioned, is actuated by means of the wheel upon the shaft of the platen-roller. The gearing is designed so as to give two, three, or more revolutions of the paper-roller to one revolution or a partial revolution of the fixed pointer upon the spindle before mentioned.

It will be seen that when the platen-roller is revolved in feeding the paper the fixed pointer covers a given area and makes a partial revolution upon the face of the case in proper proportion to the rate of rotation and the position of the said paper-roller until the pointer is stopped, as hereinafter explained. The pressure upon the knob, loosely attached

to the back of the spindle, moves the wheel, which is fixed thereon, out of gear with the rest of the train of wheels and pinions. A spring is attached, one end to the spindle, the other end to the case, so as to bring the spindle and the hand back to zero, when it is forced out of engagement with the rest of the train, as before mentioned. The band or rim which joins the two plates together and forms the case is slotted in such a way as to admit of a mechanism consisting of a box which slides in the slot and can be clamped at any convenient position on the outer and upper part of the rim of the said case and having the necessary clamping-screw for the purpose of retaining it in the required position. The box also contains a small sliding rod having a hand or stop fixed thereto, which hand rests normally upon the face of the case in such a position as to arrest the passage of the pointer, and so stop the platen-roller in any desired position. The rod, with the hand, has a longitudinal motion in the box and is retained, by means of a spring, close home to the face of the plate.

In order that my said invention may be better understood, I will now proceed to describe the same with reference to the drawings accompanying this specification, in which—

Figure 1 is a side elevation of the attachment. Fig. 2 is a front elevation. Fig. 3 is an elevation of the opposite side to Fig. 1. Fig. 4 is a similar view to Fig. 1, with the clamp and front plate removed. Fig. 5 is a similar view to Fig. 3, with the clamp and front plate removed. Fig. 6 is view of front plate removed to show the sliding piece hereinafter referred to. Fig. 7 is side elevation of Fig. 6. Figs. 8 to 14 show details herein-after referred to.

The same letters of reference are employed to denote the same parts in all the views.

Referring to Figs. 1 to 7, the box forming my device consists of a back plate *a* and a detachable plate *b*, (shown separately at Figs. 6 and 7,) which fits thereon and is attached by screws *c*. (Shown dotted at Fig. 1.) *d* is a suitably-shaped shoe, into which the box *a* fits and in which it is retained by means of the screws *e*. This shoe is provided with a clamp *f*, which takes around a bar at the end of the carriage, to which it is attached by means of the screws *g*. It will of course be understood that this clamp may be varied according to the type of machine to

which the device is to be attached. In the drawings the device is shown of a shape suitable for attachment to the Yost type-writing machine.

5 *h* is a spindle, which passes through the plates *a* and *b* and is provided at one end with a fixed pointer *j* and at the other end with a milled head or knob *k*. The spindle *h* carries a gear-wheel *m*. *n* is a spring, one end of which is attached to a pin *p*, the other end being attached to the spindle *h*. *q* is a flat spring. (Shown in detail at Figs. 8 and 9.) This spring *q* is put over the spindle *h*, and when the plates *a* and *b* are screwed together, the two ends bearing against the plate *a*, the spring tends to keep the pointer *j* on the surface of the plate *a*. *r* is a pinion, with which the wheel *m* is in engagement when the pointer *j* is on the surface of the plate *a*. To 10 the same shaft as the pinion *r* is attached a gear-wheel *s*, which engages with a gear-wheel *t* on the spindle of the platen-roller. *u* is a dovetail slide, sliding in the plate *b*, provided with a keyhole-slot *v*, taking 15 around the spindle *h*. The said spindle *h* has a circumferential groove *w* cut around it. (This is shown dotted at Fig. 6.) The purpose of this groove and sliding plate is to lock the spindle *h* in the position with the pointer 20 *j* away from the plate *a* and when the gear-wheel *m* is out of engagement with the pinion *r* by sliding the said plate along. *z* is a slot cut around the edge of the box forming the device, and in this slot *z* slides the device. 25 (Shown in detail at Figs. 10 to 14.) This device comprises a box 1, as shown in section at Fig. 14. This box 1 contains a small sliding rod 2, carrying at one end a head or stop 3, the other end being enlarged to slide in the 30 box 1 and provided with a milled head 4. 5 is a spring between the enlarged portion of the rod 2 and a stop 6 inside the box 1 for keeping the stop 3 normally on the surface of the plate *a*. 7 is a milled head provided with 35 a screw 8, which passes through a plate 9, to which the spring-box 1 is attached. The screw when in position passes through the slot *z* and screws into the small plate 10, which is so shaped as to slide on the inside of 40 the groove *z* that the box 1 may be drawn round into any position in the slot *z* and clamped in position.

The action of the device is as follows: 45 When it is desired to obtain a vertical adjustment and regulate the position of a certain line upon the paper, the box 1 is drawn round and clamped in its proper position upon the outer rim of the case. If necessary, 50 graduations may be provided around the edge of the plate *a* to indicate the required position for any particular class of type-writing machine. As the platen-roller rotates the pointer *j* is rotated by means of the gear-wheels, until it comes into contact with 55 the stop 3, when the motion of the platen-

roller is arrested. To enable the action to be continued, all that is necessary is to push the milled head 4, thus pushing out the stop 3, when the stop is raised sufficiently to release the pointer *j*, and coming down again 70 it rests upon the top of the said pointer *j*, when the platen-roller is allowed to continue its rotation. To bring the pointer *j* back to zero it is only necessary to press the knob *k*, attached to the spindle *h*, inward, so as to force 75 the wheel *m* out of engagement with the pinion *r*, when the pointer *j* will at once return to its zero position under the influence of the spring *n*. When it is desired to keep the mechanism out of action entirely for a time, 80 it is simply necessary to push in the head *k* and slide the plate *u* along, as previously described. When the slide *u* is again pulled out, the wheel *m* comes into engagement, 85 owing to the action of the flat spring *q*. When desired, more than one of the spring-boxes 1 may be employed, should it be required to stop the rotation of the platen-roller at more than one predetermined point.

What I claim, and desire to secure by Letters Patent of the United States of America, 90 is—

1. In a device of the character described, the combination with the platen-roller, of a frame removably mounted adjacent said roller, an adjustable stop mounted in said frame, a transverse shaft, a gear-train driving said shaft from said platen-roller, a pointer carried by said shaft and adapted to engage with said stop to prevent further rotation of said platen-roller, means for temporarily displacing said stop to allow said pointer to pass, and means for permanently displacing said transverse shaft to move said gear-train out of operation, substantially as 100 described.

2. In a device of the character described, the combination with the platen-roller, of a frame removably mounted adjacent said roller and comprising a base member and 110 two side members fastened within said base member, an adjustable stop mounted between said side members, a downwardly-projecting arm extending from said stop, a spring normally holding said arm against one of said side members, a transverse shaft mounted in said side members, a gear-train driving said shaft from said platen-roller, a pointer carried by said shaft and adapted to engage with said arm on said stop to prevent further rotation of said platen-roller, and means for displacing said transverse shaft to disconnect 115 said gear-train, substantially as described.

3. In a device of the character described, the combination with the platen-roller, of a frame removably mounted adjacent said roller and comprising a base member and 125 two side members fastened within said base member, an adjustable stop mounted between said side members, a downwardly-pro-

jecting arm extending from said stop, a
spring normally holding said arm against one
of said side members, a transverse shaft
mounted in said side members, a gear-train
5 driving said shaft from said platen-roller, a
pointer carried by said shaft and adapted to
engage with said arm on said stop to prevent
further rotation of said platen-roller, a spring
normally holding said pointer against said
10 side member, means for permanently dis-
placing said transverse shaft to disconnect
said gear-train until said shaft is released,
and means for automatically moving said
shaft to again connect said gear-train when
released, substantially as described. 15

In testimony whereof I affix my signature
in presence of two witnesses.

SIDNEY HERBERT DONALDSON.
